Primary Examiner — Carla Jobe Wright*Assistant Examiner* — Holly E Thurman(74) *Attorney, Agent, or Firm* — Jessica Costa**CLAIM**

The ornamental design for a portable electronic device case, as shown and described.

DESCRIPTION

FIG. 1 is a top, right, front perspective view of a portable electronic device case showing my new design;

FIG. 2 is a bottom, left, front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines of FIGS. 1–8 illustrate portions of the portable electronic device case that form no part of the claimed design.
